US00D809777S

(12) **United States Design Patent** (10) **Patent No.:** **US D809,777 S**
(45) **Date of Patent:** **** Feb. 13, 2018**

(54) **CARRIER FOR WINE GLASS**

(71) Applicant: **Hyung Ho Lee**, Chungcheongbuk-do (KR)

(72) Inventor: **Hyung Ho Lee**, Chungcheongbuk-do (KR)

(**) Term: **15 Years**

(21) Appl. No.: **29/582,160**

(22) Filed: **Oct. 25, 2016**

(30) **Foreign Application Priority Data**

May 31, 2016 (KR) 30-2016-0026350

(51) **LOC (11) Cl.** **09-02**

(52) **U.S. Cl.**

USPC **D3/202**; D7/619.1

(58) **Field of Classification Search**

USPC D3/201, 202, 315, 318, 321, 328; D7/509, 503, 507, 522, 524-528, 537, D7/601, 602, 619.1, 619.2, 624.1, 624.2, D7/624.3; D9/414, 420, 435, 444, 455; 215/382; 220/703, 705, 592.12, 592.17; 229/128; 362/101

CPC A47G 19/2255; A47G 19/2205; A47G 19/28; B65D 21/02; B65D 21/00; A45F 2003/205; A45F 3/20

See application file for complete search history.

(57) **CLAIM**

The ornamental design for a carrier for wine glass, as shown and described.

DESCRIPTION

FIG. 1 is a perspective view of the carrier for wine glass; FIG. 2 is a front view of the carrier for wine glass shown in FIG. 1;

FIG. 3 is a rear view of the carrier for wine glass shown in FIG. 1;

FIG. 4 is a left view of the carrier for wine glass shown in FIG. 1;

FIG. 5 is a right view of the carrier for wine glass shown in FIG. 1;

FIG. 6 is a top view of the carrier for wine glass shown in FIG. 1;

FIG. 7 is a bottom view of the carrier for wine glass shown in FIG. 1; and,

FIG. 8 is another perspective view of the carrier for wine glass, shown with a wine glass as environment.

The broken lines showing a wine glass in FIG. 8 illustrate environment and form no part of the claimed design.

1 Claim, 7 Drawing Sheets
